(57) **CLAIM**

The ornamental design for a prosthetic foot for use with a cycling pedal as shown and described.

DESCRIPTION

FIG. 1 is a right-rear perspective view of the prosthetic foot for use with a cycling pedal, showing our new design.

FIG. 2 is a left-bottom perspective view of the prosthetic foot for use with a cycling pedal of FIG. 1.

FIG. 3 is a rear end view of the prosthetic foot for use with a cycling pedal of FIG. 1.

FIG. 4 is a right side view of the prosthetic foot for use with a cycling pedal of FIG. 1.

FIG. 5 is a front end view of the prosthetic foot for use with a cycling pedal of FIG. 1.

FIG. 6 is a left side view of the prosthetic foot for use with a cycling pedal of FIG. 1.

FIG. 7 is a top view of the prosthetic foot for use with a cycling pedal of FIG. 1, with the front end at the top of the sheet.

FIG. 8 is a bottom view of the prosthetic foot for use with a cycling pedal of FIG. 1, with the front end at the bottom of the sheet.

FIG. 9 is a left side view of the prosthetic foot for use with a cycling pedal of FIG. 1, connected to an exemplary prosthetic leg that is shown in broken lines and forming no part of the design.

FIG. 10 is a left side view of the prosthetic foot for use with a cycling pedal of FIG. 1, connected to an exemplary cycling cleat that is shown in broken lines and forming no part of the design; and,

FIG. 11 is a left side view of the prosthetic foot for use with a cycling pedal of FIG. 1, connected to an exemplary cycling cleat that is connected to an exemplary clipless cycling pedal, the cleat and pedal being shown in broken lines and forming no part of the design

1 Claim, 8 Drawing Sheets
